UNITED STATES PATENT OFFICE.

CHARLES J. THOMAS, OF BROOKLYN, NEW YORK.

KITE-TROLLEY.

1,211,896.

Specification of Letters Patent.

Patented Jan. 9, 1917.

Application filed October 31, 1914. Serial No. 869,546.

To all whom it may concern:

Be it known that I, CHARLES J. THOMAS, a citizen of the United States, and resident of the borough of Brooklyn, in the county 5 of Kings and State of New York, have invented certain new and useful Improvements in Kite-Trolleys, of which the following is a specification.

This invention relates to improved means 10 for conveying certain articles along the cord of a kite previously floated in the air, and causing them to fall toward the ground at a suitable distance from the point whence they are despatched. Reference is made here 15 to such articles as a life-line, a message, a parcel of advertising matter, and the like.

The prime object of the invention is to provide a safe and reliable method of casting 20 a life-line from a wrecked ship to a neighboring shore, or vice versa from the shore to the ship, so that in either case the purpose sought of rescuing people from a perilous situation may be speedily accomplished.

25 A secondary object is the production of an economical and conveniently operated device wherewith information of appropriate character,—commercial announcements for example,—may be swiftly carried to some 30 desirable locality, and by repetition, widely disseminated.

Further objects will be perceived upon perusal of the detailed description of the invention hereinafter given.

35 With the said objects in view, the invention consists of the peculiar construction, arrangement, and combination of parts herein specified, illustrated in their preferred embodiment in the annexed drawing, and 40 defined in the subjoined claims.

In the said drawings:—Figure 1 is a side elevation of this improved device, shown 45 in connection with an ordinary kite, the string normally holding the latter being broken away; Fig. 2 is a rear elevation of the device, looking from the left-hand side of Fig. 1; and Fig. 3 is a development of a frame forming part of the device.

In these views, the numeral 5 represents a 50 kite of usual type, held floating in the air by a string or cord 6 of apposite length. Upon the string or cord 6 is placed a wheeled carrier comprising a pair of sheaves 7, 8, mounted tandem thereon, and a frame 55 designated as a whole by the reference nu-

meral 9. These sheaves are conveniently made of light wood, while the frame may consist of sheet-metal, also of mediocre weight. As shown by the development, Fig. 3, the said frame 9 and the appurtenances 60 thereof are preferably stamped out of the sheet metal in one piece, and so formed or designed that certain of the parts can be bent or folded relatively to others, at the several places indicated by the dotted lines 65 in the last named figure. The respective purposes of the various frame parts will presently be explained. The body of the said frame constitutes a parallelogram formed of two side members 11, 12 and two 70 end members 13, 14. The members 11, 12, it will be seen are adapted to be turned up edgewise along the lines 15, 16 where they join the members 13, 14 and the latter are likewise capable of being bent on central 75 lines 17, 18, so as to assume a V-shaped transversely of the frame. From the outer edges of the side members, respectively, project two pairs of lugs 19, 20 having perforations 21, 22, arranged to come in alignment with each other, as the several said 80 members are being turned or bent to their assigned positions. Thus constructed and shaped the frame is well adapted to receive between its said side members 11, 12 the 85 aforesaid sheaves 7, 8, whose axles 23, 24, have their bearings in the alined perforations 21, 22, of the paired lugs 19, 20, respectively. The kite cord 6 is passed under these sheaves, so they will ride thereon, in 90 a manner that is well understood. It will be observed that they cannot jump off the kite-cord since the cross members 13 and 14 of the frame 9 act as retainers therefor, as well as the deep opposite flanges or 95 cheeks of the sheaves themselves, between which the cord is normally confined laterally, as best seen in Fig. 2. The lugs 19, 20 also coact with the side members of the frame in keeping the sheaves from wabbling, and in maintaining them properly 100 alined.

Pendants 27, 28, are provided on the frame 9, the same being preferably formed integral with the sides thereof, somewhat in advance of the rear pair of lugs 20. As shown, 105 these pendants are made to fold downward on the lines 29, 30, Fig. 3, in such a manner that they will run parallel one with the other in the planes of their respective side 110

members, 11 and 12. Each pendant has a lateral projection 31, 32 extending out at right angles therefrom, as further represented in said figure. The projection 31 is located by preference, at the outer extremity 5 of the pendant 27, and by bending it successively on the lines 33, 34, 35 it is brought over and around the corresponding extremity of the pendant 28, so as to constitute a tie for and between the said pendants. Analogously, the projection 32, which is placed a little higher up on the pendant 28, is bent on the lines 36, 37, 38 and caused to unite the side opposite preferably, as 15 illustrated in Figs. 1 and 2.

To the lower end of the pair of pendants aforesaid is pivotally connected a bearer 41, intended to carry the life-line, missive, advertisement, or other object to be sent up the kite-cord. This element 41 is conveniently fashioned out of a single wire, doubled upon itself centrally to form an elongated loop 42, then twisted as at 43, and led out from this point on parallel lines to opposite 25 perforations in the pendants, through which the ends of the wire are hooked, as at 44, 45, midway between the ties formed by the above described projections 31, 32. The bearer 41 is thus hingedly connected with 30 the pendants, but at the same time it is limited in its movements thereon by the said projections, which act as stops for the bearer as well as ties for the pendants. As seen in Fig. 1 the bearer may be swung upward on 35 the pendants to a line approximately parallel with the frame 9, but it may not rise much higher, owing to the presence of the stop afforded by the tie or projection 32. If released, the bearer may drop down to a 40 vertical position, as indicated by dotted lines 41^a in Fig. 1, and by full lines in Fig. 2. In the latter case, however, the tie or projection 31, will serve as a stop to prevent movement of the bearer farther backward. 45 When used for carrying objects up the kite-cord, the bearer 41 is held at its free end by a detent 48, connecting the latter with the forward part of the before described wheeled carrier. This detent also is conveniently 50 made of wire, bent forwardly at 49 to form a hook adapted to engage the loop 42 of the bearer. Another bend 50 of the wire detent 48 enables it to be brought up to a point 55 near the frame 9, where its rear end is passed through hangers 51, 52, depending from the transverse end member 14 of the said frame, and still another bend 53 will prevent this end of the wire from being drawn out of the said hangers entirely, 60 though the interval left between the bends 50 and 53 is sufficient to allow for the sliding of the detent back and forth so as to permit either engagement with or disengagement from the aforesaid loop of the bearer.

65 The numeral 55 represents a life-line at

tached to a centrally-apertured disk 56, through which the bearer 41 is passed so as to keep it in suspension while being conveyed up the kite-cord; 57 designates a variant form of disk which may be used for 70 advertising purposes. A number of such disks may be employed simultaneously, according to the length and capacity of the bearer to carry the several objects, as will be readily understood.

A sail 59, which may be a card or other suitable material, furnishes the power wherewith the wheeled carrier is propelled up the kite-cord, together with the said bearer and the object or objects thereto attached. A card is used by preference, when the device is utilized for the purpose of distributing advertisements. As shown, the sail or card 59 is made to rest at its lower edge within a depression 60, formed in the bearer 41, and to press against wings 61, 62 projected outwardly from the frame sides 11, 12. Like the other adjuncts of the frame, these wings are made integral therewith, and arranged to fold at right angles to the same 85 on the lines 63, 64. A notch 65 is cut out of the upper edge of the said card 59, centrally, to enable it to be positioned transversely of the bearer and with opposite portions evenly balanced on the sides of the 90 carrier.

It will be noted that the axle of the rear sheave 8 is located a little above the frame 9, whereas the axle of the forward sheave is practically at the juncture of the paired lugs 100 19 with the sides of the said frame. This mode of construction has proven more satisfactory than in the case where the sheaves are mounted on a level line, because as may be inferred by looking at Fig. 1, the elevated 105 sheave allows a little more play to the kite-cord, which tends to accelerate the movement of the carrier thereon, due to the lashing effect developed by the swaying of the 110 cord under the sheaves.

A stop 66 is placed on the cord 6, at the required distance from the kite 5, in a position to encounter and operate the aforesaid detent 48, when the objects carried by the bearer 41 have reached the desired elevation. 115 This stop may consist of a piece of cork, or other light material, placed up against a knot 67 on the cord. The said cork-stop is split along one side as at 68, so that it may straddle and cling to the cord. As the detent 48 is brought up against the stop (dot and dash line 66^a) the latter operates to detain the detent while the frame is carried forward through the action of the wind. In this way the detent is slid back as shown by the dot and dash lines 48^a in Fig. 1, whereupon the loop 42 of the bearer 41 becomes disengaged from the hook 49 of the detent, the bearer is released, and the objects then 120 on the latter are let fall upon the ground.

Having described my invention what I desire to secure by Letters Patent and claim is:

1. A kite trolley comprising a carrier arranged to ride upon the kite-cord, an object bearer thereunder operatively mounted in substantial parallelism with both the carrier and cord, a flexible connection keeping said bearer permanently suspended by one end, and means releasably holding the other end of the bearer so that it may be dropped to discharge the object.
2. A kite-trolley comprising a carrier adapted for riding along the kite-cord, a rigid pendant under one end thereof, an object bearer pivotally connected by one end to said pendant, and a slidable detent holding the other end of said bearer.
3. A kite-trolley comprising a carrier adapted to ride on the kite-cord, an object bearer held suspended from said carrier in substantial parallelism therewith, and a sail detachably set between the carrier and said bearer.
4. A kite-trolley comprising a carrier riding upon the kite-cord, a bearer hingedly connected to said carrier at one end, a detent holding up said bearer by its other end, a sail resting upon the bearer intermediately thereof, and means on the carrier arranged to maintain said sail in its operative position.
5. A kite-trolley comprising a carrier adapted to ride upon the kite-cord, an object bearer operatively mounted in substantial parallelism with said carrier and pivotally connected thereto at one end, a detent hold-

ing the other end of said bearer releasably suspended from the carrier, a sail transversely seated in a depression of the bearer, and projections on the carrier supporting said sail against the wind pressure.

6. A kite-trolley comprising a carrier with sheaves adapted to ride upon the kite-cord, said carrier including a frame the members whereof constitute retainers serving to maintain said cord within said sheaves, an object bearer operatively connected with the carrier, and a stop on the lower portion of the latter for said bearer.

7. A kite-trolley comprising a carrier arranged to ride along the kite-cord, a pair of fixed pendants projecting from said carrier, an object bearer hinged between said pendants, a detent releasably holding the other end of said bearer from the carrier, and a stop extending between the pendants to limit the movement of the bearer.

8. A kite-trolley comprising a carrier adapted for riding upon the kite-cord, said carrier consisting of a frame with sheaves mounted at different levels therein, retainers on said frame limiting the movement of said cord to and from either sheave, an object bearer suspended from the carrier, and means for releasing the object from said bearer.

Signed in the borough of Manhattan, in the county of New York and State of New York, this 17th day of October, A. D. 1914.
